Primary Examiner—Raphael Barkai**Attorney, Agent, or Firm**—Richard B. O'Planick; Lisa B. Riedesel**[57] CLAIM**

The ornamental design for a toy wagon, as shown and described.

DESCRIPTION

FIG. 1 is a top right front perspective view of a toy wagon showing our new design;

FIG. 2 is a top plan view thereof;

FIG. 3 is a left side elevational view thereof, the right side elevational view being a mirror image;

FIG. 4 is a front elevational view thereof;

FIG. 5 is a rear elevational view thereof; and,

FIG. 6 is a bottom plan view thereof.

The broken lines are for illustrative purposes only and forms no part of the claimed design.
